UNITED STATES PATENT OFFICE.

GEORGE A. COLTON, OF SYRACUSE, NEW YORK, ASSIGNOR OF ONE-HALF
TO HENRY C. HOOKER, OF SAME PLACE.

LATHE-CHUCK.

SPECIFICATION forming part of Letters Patent No. 295,230, dated March 18, 1884.

Application filed January 25, 1884. (No model.)

To all whom it may concern:

Be it known that I, GEORGE A. COLTON, a citizen of the United States, residing at Syracuse, in the county of Onondaga and State of New York, have invented certain new and useful Improvements in Lathe-Chucks, of which the following is a specification, reference being had therein to the accompanying drawings, in which—

10 Figure 1 is a perspective of a chuck constructed in accordance with my invention. Fig. 2 is a central vertical section of the same. Fig. 3 is a side elevation of a jaw, its operating-screw, and a jaw-carrier and its operating-screw, shown detached and in relative co-operative positions. Fig. 4 is a rear view of the chuck-body with a slight portion broken away. Fig. 5 is a side elevation of a jaw-operating screw. Fig. 6 is a top view or plan of a jaw-carrier. Fig. 7 is a perspective of a jaw inverted. Fig. 8 is a perspective of a concentric boss or abutment detached. Fig. 9 is a plan and edge view of a gear-ring; and Fig. 10 is a central vertical section of an arm and 25 a portion of the chuck body or case, the jaws and adjuncts being removed.

Like letters refer to like parts in all the figures.

This application is a division of a companion application filed by me March 21, 1883, Serial No. 88,942, in which certain features hereinafter specified, but not claimed, are presented and claimed.

The object of my invention in this instance is with reference to chucks generally, (whether of that class having jaws moving in unison and concentrically, or of that class having jaws moving independently, or of that class having jaws moving or adapted to be moved at will, 35 either in unison or independently) to devise a body or case for any chuck, which body or case shall have such features of construction, contour, and internal conformation as to be capable of being cast in one piece, conveniently presentable to machine-tools for the purpose of fitting said body or case for the reception of the movable parts of a chuck located therein or thereon, and capable of holding irregular work and of being employed in 45 connection with the usual form of lathe-dogs to revolve work upon centers, thus serving as

a special face-plate, and avoiding the necessity of frequent removals or detachments of the chuck from the lathe-spindle in order to prosecute work requiring the use of dogs.

Furthermore, the object of my invention is to construct the movable parts of a chuck in such forms and for such relative arrangement in the body or case as will co-operate with a body or case having the above-mentioned characteristics, whereby the hand-work required in fitting the elements of a chuck is reduced to a minimum, and the cheapness, simplicity, and accuracy of machine-tool work is made available, and this, too, without a departure from machines of usual and popular forms, in contradistinction to special machine-tools—that is to say, in the manufacture of chucks constructed in accordance with my invention, the hand-work or work with hand-tools is reduced to the minimum, and ordinary lathes, planers, and drills suffice for a proper and accurate construction of and stability, firmness, and smoothness of co-operation in the elements.

Other objects and advantages of my invention will appear in the following description, and the novel features thereof will be specifically set forth in the claims.

The body or case which I have devised to meet the requirements in view consists of a single casting comprising a central hollow hub, A, having a number (four in this instance) of hollow radial arms, A'. The hub A is provided with a diaphragm or floor, A², which is centrally apertured, as usual, for the passage of tool-shanks or work. The floor A² is located in the same plane with the inner or bottom walls, a, of the ways A³, in which the jaws are mounted, so as to support the same when they are projected into the hub, and this function is performed whether the jaws are constructed in one or several pieces, for in case single-piece jaws are employed they are made to extend to the lower ways in each arm, as hereinafter described.

All of the arms A' being alike, a particular description of one is sufficient; so, also, with reference to the jaws and their adjuncts.

The rear portion of the arm is cast with a closed end, which is subsequently bored to form a bearing, A⁴, for one end of a jaw-oper-

ating screw, or, as in this instance, for the jaw-carrier-operating screw B, the other enlarged bearing, A⁵, being formed in the wall of the hub A. The arms A' being oppositely disposed in this instance, it will be noticed that when the body is placed properly on or in any ordinary drilling-machine the bearings in two arms may be formed at one operation, and by using a well-known form of boring-tool the seats or shoulders A⁶ may be easily and accurately formed for the usual wrench and for a bevel-gear upon the screw B employed in the form of jaw shown. The upper or outer surfaces of the bearings A⁴ A⁵ serve as and constitute a portion of the inner or bottom wall, a, of the way A³ for a jaw or the jaw-carrier employed in this instance, while the side walls, a', are cast in the rough and subsequently finished in an ordinary planer, the opposite disposition of the arms again resulting advantageously, in that a single operation finishes the ways in both arms and the adjacent portions of the surface of the diaphragm or floor A². In like advantageous manner the outer ways, A⁷, are formed, the bottom or inner walls, a', thereof being an inset and in a common plane with the outer or upper surface of the jaw-carrier C employed in this instance, so that the independent jaw E employed in this instance has a bearing in the body and upon the carrier. Forming the inset produces an outer or upper wall, a², whereby a L form of independent jaw E is used, so that it is held against upward movement and always in contact with the carrier.

Referring now to Fig. 4, a circular depression is formed in the hub, leaving a shoulder, a³, and may be accurately finished in the ordinary lathe, so that when the body is mounted on any suitable boss, by means of bolts seated in the holes a⁴, it will be concentrically mounted on any lathe-spindle to which said boss has been screw-threaded, and subsequently turned or fitted while on said spindle—a matter that renders the attachment of the complete chuck to any lathe a matter of greater convenience than when said boss or spindle-seat is formed as a part of the hub or complete chuck, which might be done, though, for the above reasons, not preferably.

It will be seen by the foregoing description that the general outline and internal construction of the body or case preserves all of the usual advantageous features of popular chucks, and secures advantages not possessed by them, and is also formed of a single integral casting and capable of receiving irregular work, portions of which may project rearwardly between the arms, and those portions designed to be finished or bored thus brought to the center, which could not be so positioned were the body a complete cylinder.

Attention is now directed to the construction of the movable parts of the chuck and their adaptability to each other and to the body or case.

The first element noted is the jaw-carrier

screw B. (See Figs. 2 and 3.) It comprises a body, b, squared at b' for a wrench, is provided with a left-hand screw-thread, b², an enlarged cylindrical bearing or journal portion, b³, a still larger thrust-shoulder, b⁴, a cone-gear, b⁵, and a projecting cylindrical, or it may be other shaped, end-thrust projection, b⁶, all of which features are formed of or as one piece. The body b fits the bearing A⁴, the enlarged portion b³ fits the enlarged bearing A⁵, and the thrust-shoulder b⁴ fits the bearing or seat A⁶, while the thrust end b⁶ bears against a central core, F, and in a flat seat, f, formed in the periphery thereof. Said seat f, however, may be changed in form to any degree so long as the thrust end b⁶ conforms thereto—as, for example, a cone shape; but a flat seat and thrust end are preferred.

It is deemed important that the entire screw B may be made on centers, its bearings, screw-thread, thrusts, and gear all being formed accurately and readily by existing machine-tools. If preferred, the gear may be made separately and attached to or mounted rigidly upon the end thrust.

The jaw-carrier C is also a single piece, and comprises a depending lug, c, screw-threaded for the reception of the thread b² of the screw B, the body c' of the carrier being adapted to fit the way A³, its upper face being flush with the walls a' of the way A⁷, as before stated. The upper surface of the jaw-carrier is recessed (see Fig. 6) to form two bearings, c c', and a thrust-bearing, c², for the independent jaw-screw D, which, like the screw B, is made of a single piece, (see Fig. 5,) and comprises a body, d, squared at d' for a wrench, and provided with a screw-thread, d², formed on an enlargement of the body, whereby thrust-shoulders d³ d⁴ are made, a bearing, d⁵, and an enlarged end portion, d⁶, forming thrusts or thrust shoulders d⁷ d⁸. When within the bearings of the jaw-carrier, the thrust d⁷ bears against the thrust-bearing c², the thrust d⁸ against the adjacent end of the bearing c', the thrust d⁴ on its opposite end, and the thrust d⁶ on the adjacent end of the bearing c, so that the draft or strain on the screw D in either direction is firmly resisted, and a sure, firm, servicable hold is given to the parts concerned.

The independent jaw E (see Figs. 2, 3, and 7) has oppositely-arranged side ribs, e, giving it a L form, to fit the inset of way A⁷, and is screw-threaded on its under surface throughout its entire length, to fit the screw D, while the unthreaded portions of said surface are adapted to bear upon the walls a' of said inset and upon the upper surface of the carrier, thus relieving the carrier from undue pressure while work is being clamped by the jaws, and at the same time giving a broad bearing or base to the independent jaw against transverse strains, which tend to spring them out of a true vertical line to the face of the chuck.

The core F is fitted to enter the hub and rest against the under side of the diaphragm or floor A², thus re-enforcing the same against press-

ure exerted thereon by the inner ends of jaws or jaw-carriers when holding small work, while the outer end of the core and of its flange f' is sustained against such pressure by the lathe-spindle boss before described. This feature of supporting the inner ends of jaws by a core so supported, is available whether the jaws be of a single piece or of two or more pieces.

10 A geared ring, G, which serves to communicate motion from one of the geared screws B to the others in the series, is mounted on the core F and rests upon its flange f' , as shown, and its tendency to move backward from the gears when force is employed is overcome by the security with which the core is held to place, as above described.

15 The operation of the chuck is apparent from the description given—that is to say, by turning with any suitable wrench any one of the screws B, all of the jaws E are moved in or out from the center, according to the direction in which the screw is turned, and by turning any one of the screws D that jaw E which is 20 mounted on said screw is moved in or out independently of the remaining jaws and carriers.

25 If a single integral jaw or jaws are employed in a body or case having the features described, and formed of a single casting, the screws D 30 would be omitted, and the jaw and carrier would be integral.

35 I do not broadly claim a chuck having jaws capable of independent and common movement, nor do I claim the use of bevel-geared screws in connection with a geared ring for such common movement of the jaws. Furthermore, I do not in this instance claim the independent jaw and screw in connection with the carrier having the lug and with the geared 40 screw and ring, nor such elements when the carrier-screw gear is provided with a thrust-shoulder, as this subject-matter is claimed in the above-mentioned companion application. Furthermore, I do not wish to be understood 45 as herein limiting my invention to the exact details and proportions of the chuck shown, but reserve my right to alter the same in any manner and to any extent within the skill of persons conversant with the construction of 50 chucks, for it is evident that minor features may be altered and yet many advantages of an integral body over one formed in parts for the introduction and support of the movable elements may be retained. The larger inner bearing, A⁵, for example, which permits the 55 passage of the screw-threaded portion of the screw B, may be omitted, and a removable collar and gear be substituted, the former as and for the bearing A⁴, and the latter for the 60 fixed gear b⁵, whereby the screw B might be inserted from and at the outer end of an arm, A', and still the body be cast in one piece. Other minor changes may be made 65 without loss of advantages arising from my novel features of construction. A tight compartment is formed by the hub-walls, the floor

A², and the core, in which the bevel-gears and ring are located, whereby no dust, grit, or dirt can clog these parts, and it is evident that this advantage might be retained and 70 yet other features of the parts involved may be omitted.

Having described my invention, what I claim is—

1. A chuck body or case comprising a hub 75 and radial arms, the latter provided with ways for jaws or jaws and jaw-carriers, substantially as specified.

2. A chuck body or case comprising a hub 80 and projecting radial jaw-supporting arms, 85 the whole being cast in one piece, substantially as specified.

3. A chuck body or case comprising a hub, 90 and hollow radial arms having internal bearings, as A⁴ A⁵, the whole being formed in one piece, substantially as specified.

4. A chuck body or case comprising in a single casting a hub, and hollow radial arms projecting therefrom and having an outer bearing, as A⁴, and an inner enlarged bearing, as A⁵, 95 in combination with a jaw or jaw-carrier-operating screw having an enlarged bearing portion, as b³, substantially as specified.

5. A chuck body or case comprising in a single casting a hub, hollow radial arms, a diaphragm or floor, jaw-ways, and thrust seats or shoulders, substantially as specified. 100

6. The screw B, comprising the body b, thread b², bearing b³, gear b⁴, and thrusts or shoulders b⁵ b⁶, substantially as shown and described. 105

7. The screw D, comprising the body d, bearing d², and thrusts d³ d⁴ d⁵ d⁶, substantially as shown and described.

8. The combination of the jaw E and screw D, having thrusts d³ d⁴ d⁵ d⁶, with the carrier 110 having the bearings c c' c'', substantially as shown and described.

9. The combination of the arm A', having the bearings A⁴ A⁵, and formed as a part of the hub A, having seat A⁶, the screw B, having the body b, enlarged portions b³ b⁴, and a jaw or a jaw-carrier, substantially as specified. 115

10. The combination, with the chuck-body having the hollow radial arms provided with ways, and a diaphragm or floor, A², of jaws or jaw-carriers adapted to said ways, and a core, as F, arranged against said diaphragm or floor, substantially as specified.

11. The screw D, having the enlarged portion d⁶, forming the thrusts or shoulders d³ d⁴ at its inner end, substantially as specified. 120

12. The hub A, having bearings A⁵ and floor A², in combination with the core F, having flange f', and with geared ring G and bevel-gears b⁵, substantially as specified. 125

In testimony whereof I affix my signature in presence of two witnesses.

GEORGE A. COLTON.
